UNITED STATES PATENT OFFICE

2,457,965

REPLACEABLE FURNACE ARCH NOSE
CONSTRUCTIONWilliam George Young, Chicago, Ill., assignor to
Chicago Fire Brick Company, a corporation of
Illinois

Application October 30, 1944, Serial No. 561,081

7 Claims. (Cl. 110—99)

1

The present invention relates to furnace arches and more particularly to means whereby sectional nose arches may be repaired and replaced from the exterior of the furnace. It is the particular purpose of this invention to provide a novel construction whereby one or more sections of a furnace nose arch can be lifted out and replaced without disturbing the remainder of the installation.

The detailed advantages of my invention will appear more fully as the description proceeds in connection with the accompanying drawings. It should be understood, however, that the drawings and description are illustrative only and should not be taken as limiting the invention except insofar as it is limited by the claims.

In the drawings, Fig. 1 is a longitudinal sectional view of a portion of the furnace arch to which my invention is applied;

Fig. 2 is a fragmentary sectional view taken on the line 2—2 of Fig. 1;

Fig. 3 is a sectional view on the line 3—3 of Fig. 1; and

Fig. 4 is a perspective view of the various castings that support the nose arch of the furnace.

Referring now in detail to the drawings, the present invention is embodied in a furnace roof arch. The supporting structure for the arch comprises channel members 10 and 11. Since the present invention is concerned only with the nose arch, the details of the mounting of the roof arch beyond the nose are not shown. The channels 10 and 11 have secured thereto a plurality of spaced parallel castings 12 and 13, which are adapted to support a series of like tile hangers 14. The tile hangers 14 are utilized both in the flat part of the roof and in the nose. The castings 12 are bolted by suitable bolts 15 to the channel member 10. These castings are spaced apart a distance equal to twice the thickness of the tile members to be supported from them. It will be noted that each of the castings 12 has oppositely directed flanges 16 and 17 along its lower edge and that the hangers 14 are so shaped as to engage the flanges 16 and 17 so that the hangers can slide along the flanges.

The castings 13 are mounted in uniformly spaced relation along the channel 11. These castings 13 have hook portions 18 which engage with an angle iron 19 that is welded to the back of the channel iron 11. The castings 13 are also secured to the channel by suitable bolts 20. The castings 13 are provided with shelf portions 21 for supporting individual fire brick 22 that constitute an apron wall over the nose arch of the furnace. The castings 13 are also provided with

2

flanges 23 adjacent the lower ends, these flanges serving to support one or more of the hangers 14, by means of which wedge-shaped nose tile 24 are supported. It will be noted that the castings 13 have the flanges 23 continued at 25 and 26, the portions 25 of the flanges serving as stops to limit the movement of the hangers 14.

An inspection of Fig. 1 will show that the two castings 12 and 13 have their end portions that face each other aligned and spaced apart so as to provide an open space 27. The castings 12 and 13 also have shelf portions 28 and 29 along the top of their adjacent ends. These shelf portions project upwardly so as to provide shallow recesses 30 and 31 immediately back of the shelf portions. This particular construction is provided to receive a bar 32 which in turn pivotally supports a hanger 33. I provide the hanger 33 with two spaced arms 34 and 35. The arms receive the central portion 20 of the bar 32 between them. Also the arms and the bar are drilled to provide passage for a pivot pin 36 which pivotally connects the parts together.

The hanger 33 has oppositely directed projections 37 and 38 at its lower end. These projections are directed outwardly and upwardly at an angle so as to be received in the recesses 39 of adjacent tile members 40. The tile members 40 are rectangular in shape. One of the hangers 33 actually supports four tile members 40. The tile members 40 are backed up above and below by wedge-shaped tile 24 that are supported by the hangers 14. The construction of the lower ends of the hangers 14 is the same as that of the hanger 33. Likewise the tile 24 are provided with channels 39a similar to those in the tile 40. The tile in the horizontal section of the furnace roof are exactly like the tile 40 so that these particular shapes are interchangeable.

In order to seal the roof more tightly and protect the supporting structure above the tile, I prefer to cover the upper ends of the tile with sections 41 of insulation and to extend this insulation along the nose part of the arch up to the apron wall 2. The insulation may be in batts or in other suitable form.

The foregoing description is believed to be sufficient to show that I have provided an improved arch construction whereby it is possible to replace worn out tile in the nose arch from the exterior of the furnace with little difficulty. Assuming that it is desired to replace a certain section of the nose arch, the insulation 41 is removed from behind the tile 40 which are to be removed. It is then possible to lift the bar 32 with the hanger 33 and remove an entire section,

consisting of four tile and one hanger, from the nose arch. The tile 24 immediately above the removed section bind on the flanges of the hangers 14 so that they remain in place. However the repairman may work them loose and take them out through the opening provided by removing a hanger 33 and its four tile. A section consisting of the hanger 33 and the four tile can be inserted in the place of a removed section without difficulty. Moreover, when the section is removed, access can be had to the adjacent tile 24 to replace any of them.

It is believed that the nature and advantages of my invention will be readily apparent to those skilled in the art upon reading the description hereinbefore made.

Having thus described my invention, what I claim as new and desire to secure by Letters Patent is:

1. A nose arch construction for furnaces, comprising a supporting framework including pairs of oppositely disposed supporting castings having tile supporting means thereon, wedge shaped tile carried by said means at the adjacent ends of the castings, each casting of a pair having a shelf thereon, a bar resting on the shelves and providing a bridge between the two castings of a pair, a tile hanger suspended from the bar, and nose tile carried by said hanger and removably mounted thereby between the wedge shaped tile carried by the opposite castings of a pair of said supporting castings, the wedge shaped tile having their axes disposed at an angle with respect to each other, the said nose tile being as small in cross section at the furnace end as they are intermediate the ends whereby they may be lifted out by raising the bar from said shelves.

2. A nose arch construction for furnaces, comprising a supporting framework including pairs of oppositely disposed supporting castings having tile supporting means thereon, wedge shaped tile carried by said means at the adjacent ends of the castings and having their axes disposed at an angle with respect to each other, each casting of a pair having a shelf thereon, a bar resting on the shelves and providing a bridge between the two castings of a pair, a tile hanger suspended from the bar, and nose tile of substantially the same cross section from end to end carried by said hanger and removably mounted thereby between the wedge shaped tile carried by the opposite castings of a pair of said supporting castings.

3. In a nose arch, pairs of oppositely disposed supporting castings having tile supporting means thereon, wedge shaped tile carried by said means at the adjacent ends of the castings and having their axes disposed at an angle with respect to each other, each casting of a pair having a shelf thereon, the shelves of each pair being spaced apart, a bar resting on the shelves and providing a bridge between the two castings of a pair, a tile hanger suspended from and disposed intermediate the ends of the bar, and nose tile carried by said hanger within the projection of the two shelves and removably mounted thereby between the wedge shaped tile.

4. In a nose arch construction, a supporting framework having means to mount the upper and lower refractory portions of a nose arch in spaced relation, said portions including spaced sets of wedge shaped tile, the tile of each set being disposed with their axes at an angle to each other, a series of cross bars resting on said framework and spanning the space between the upper and lower portions and refractory tile assemblies sus-

5 pended from said cross bars within the projection of the space limits between the refractory portions and filling the space between said upper and lower refractory portions, said tile assemblies comprising tile uniform in cross section.

5. In a nose arch construction, a supporting framework having means to mount the upper and lower refractory portions of a nose arch in spaced relation, said portions including spaced sets of wedge shaped tile, the tile of each set being disposed with their axes at an angle to each other, a series of cross bars resting on said framework and spanning the space between the upper and lower portions and refractory tile assemblies suspended from said cross bars within the projection of the space limits between the refractory portions and filling the space between said upper and lower refractory portions, said assemblies each comprising a hanger having a bifurcated end pivoted on one of the cross bars and lateral projections upon the other end, and refractory tile hung on said projections, said refractory tile being uniform in cross-section whereby each cross bar-hanger-tile assembly is removable from the exterior of the nose arch.

6. In a nose arch, pairs of oppositely disposed supporting castings having tile supporting means thereon, wedge shaped tile carried by said means at the adjacent ends of the castings, the tile at each end having their axes disposed at an angle to each other, each casting of a pair having a shelf thereon, the shelves of each pair being spaced apart, a bar resting on the shelves and providing a bridge between the two castings of a pair, a tile hanger suspended from and disposed intermediate the ends of the bar, and nose tile carried by said hanger within the projection of the two shelves and removably mounted thereby between the wedge shaped tile, the castings having recesses behind the shelves and the bar having downwardly directed lugs at the ends extending into said recesses.

7. In a nose arch, pairs of oppositely disposed supporting castings having tile supporting means thereon, said means comprising oppositely directed flanges at the lower edges of said castings, hanger clips having opposed hook portions slidably receiving one of said flanges, and refractory tile carried by said hanger clips, the opposing, spaced portions of said castings each carrying wedge shaped tile having their axes disposed at an angle to each other, each casting of a pair having a shelf thereon, the shelves of each pair being spaced apart, a bar resting on the shelves and providing a bridge between the two castings of a pair, a tile hanger suspended from the bar, and nose tile carried by said hanger and removably mounted thereby between the wedge shaped tile.
